UNITED STATES PATENT OFFICE.

LOUIS C. REIS, OF DULUTH, MINNESOTA.

WATER-COOLED BUCKSTAY.

Application filed May 13, 1927. Serial No. 191,094.

This invention relates to a new and improved buckstay and more particularly to a water cooled buckstay especially adapted for use with furnaces such as open hearth furnaces or the like.

In furnaces of this type buckstays are placed at intervals along the sides of the furnaces and are tied together across the top of the furnace to properly support the walls and take up the thrust of the roof. The buckstays are consequently located closely adjacent the furnace walls and these walls, along the sides of the hearth, are raised to a very high temperature. In my prior patent, No. 1,402,444, January 3, 1922, I have disclosed a water cooled buckstay which is especially efficient for such use as the water cooling prevents the warping of the buckstay, due to the intense heat of the adjacent furnace walls.

The buckstay of the present application is in the nature of an improvement on the buckstay covered in my patent above-mentioned.

It is an object of the present invention to provide a new and improved water cooled buckstay comprising a plurality of associated vertical elements.

It is a further object to provide a buckstay of this type in which the various elements are formed into an integral structure, and in which the water cooling system is continuous throughout the associated vertical elements.

Other and further objects will appear as the description proceeds.

I have illustrated a preferred embodiment of my invention in the accompanying drawings, in which

Figure 1 is a perspective view of my improved buckstay; and

Figure 2 is a section taken on line 2-2 of Figure 1.

The buckstay comprises the pair of vertically extending slabs 11 and 12 which are preferably formed of wrought metal. These slabs are connected together at their upper ends by the plates 13 and 14, which plates are connected to the fabricated section 15, which latter is connected to other elements of the furnace structure which have not been shown. The lower portions of the slabs 11 and 12 are connected together by a plate 16 connected to the slabs through angle members, as indicated at 17. The lower ends of the slabs are tied together by the plate 18.

The slab 11 has the vertical water passage 19 formed therein and the slab 12 has a simi-

lar passage 20 formed therein. These passages are formed near the surfaces of the slabs which will be adjacent the hearth wall when the buckstay is incorporated in a furnace structure. The cross pipe 21 connects the bottoms of the passages 19 and 20 and is preferably welded in place. The water inlet pipe 22 is connected to the slab 12 and leads into the upper end of the passage 20. The water outlet pipe 23 is similarly connected to the upper end of the passage 19.

The passages 19 and 20 may be formed in the slabs in any desired manner, as for example, they may be milled or planed in the edge of the slab after it is rolled. The passages are then closed by flat plates 24 and 25, such as shown in Figure 2, these plates being firmly welded in a recess in the face of the slab. The water introduced through pipe 22 travels down through passage 20 in slab 12 across through pipe 21 and up passage 19 in slab 11. The water then is drawn off through pipe 23. It will be apparent that this structure affords a buckstay of very considerable strength and rigidity which, due to its adequate water cooling, will stand up under long usage even where the furnace walls are thin and very hot.

While I have shown one specific embodiment of my invention by way of example, it is to be understood that I contemplate such changes and modifications as may come within the spirit and scope of the appended claims.

I claim:

1. In a buckstay construction, a rigidly secured water cooled unit comprising a pair of vertically extending, parallelly disposed metal members said metal members having water passages formed therein adjacent their face portions, a cross connecting pipe between the bottom of said passages, means for conducting water to the top of one of said passages, means for withdrawing water from the top of the other of said passages, means rigidly securing the tops of said members in spaced relation and independent means for rigidly securing the lower ends of said members in spaced relation.

2. In a buckstay construction, a rigidly secured water cooled unit comprising a pair of vertically extending, parallelly disposed metal members, said metal members having water passages formed therein adjacent their face portions, a cross connecting pipe between the

bottom of said passages, means for conducting water to the top of one of said passages, means for withdrawing water from the top of the other of said passages, a fabricated attaching member disposed between the upper ends of said members, metal connecting strips rigidly holding the upper ends of said vertical members secured to said fabricated mem-

ber, a spacing member disposed between the lower ends of said vertical members and a ¹⁰ metal strip rigidly securing the bottom ends of said vertical members.

Signed at Duluth, Minnesota, this 6th day of May, 1927.

LOUIS C. REIS.
